UNITED STATES PATENT OFFICE

WILLIAM C. STEWART, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

GRADING MACHINE

Application filed June 18, 1919. Serial No. 305,160.

This invention relates particularly to grading machines, although not limited to use with such machines, and is herein illustrated as embodied in a machine designed to split leather blanks.

In the manufacture of boots and shoes it is desirable that certain blanks, such for example as sole blanks, should be split or skived to a uniform thickness throughout their whole extent or throughout some selected locality, the thickness of the finished blank being preferably that of the thinnest spot in said locality. It is also desirable that the finished blanks should be marked and sorted in accordance with their thickness. The term "grading", in the boot and shoe art, is used generically to cover these and similar operations such as visually indicating the thickness of a blank by means of a pointer movable over a scale.

A type of grading machine which has gone into quite extensive use is shown in British Patent No. 17,808 of 1909. In this machine the blanks are graded (in this case split and marked) automatically in accordance with the thickness of the thinnest spot in the edge of the forepart of each blank. The machine comprises the grading mechanism referred to above, feeler mechanism and mechanism responsive to the determinations of the feeler mechanism for adjusting or setting the grading mechanism. Hitherto in machines of this general type having mechanism for operating upon blanks to change some characteristic thereof, and adjusting or setting mechanism for the operating mechanism adapted to be actuated by the blanks one by one as they approach the operating mechanism, a preceding blank must have been completely operated upon before a succeeding blank could actuate the adjusting mechanism.

According to one feature of the present invention the operating mechanism and the mechanism for adjusting it are so constructed and arranged as to permit the adjusting mechanism to be actuated by a succeeding blank while the adjustment of the operating mechanism for a preceding blank is being maintained. In the illustrated machine in which the mechanism for changing a char-

acteristic of a blank is a splitting mechanism, the adjustment or setting of the splitting mechanism is maintained while a succeeding blank is operating the adjusting or setting mechanism, said last-named mechanism in the illustrated construction comprising two substantially duplicate interconnected mechanisms which operate alternately. With such a construction, the output of the machine is greatly increased.

This and other features of the invention, including certain details of construction and combinations of parts, will be described as embodied in an illustrative machine and pointed out in the appended claims.

Referring now to the accompanying drawings—

Fig. 1 is a side elevation of a machine in which the present invention is embodied;

Fig. 2 is a perspective of the plurality of setting mechanisms, and

Fig. 3 is a perspective partly in section and partly in elevation showing the two pairs of stepped wedges and the means for adjusting the upper members of the pairs.

For convenience the invention has been illustrated as embodied in a machine which is similar in many respects to that of British Patent No. 17,808 of 1909 referred to above; and parts which are similar to those of the patented machine have therefore been given the numerals which are applied to them in the patent.

Referring first to Fig. 1, the feeling or detecting mechanism comprises a feed roll 8 and a feeler roll 9 between which the blank passes, the feeler roll being yieldable while the axis of the roll 8 is stationary. Consequently, when a blank is fed between these rolls, the feeler roll 9 first moves down a distance corresponding to the thickness of the forward edge of the blank, and then moves up and down as it encounters thinner or thicker localities in the blank. An arm 21, fast to a rock-shaft 23, is moved downwardly at all times when it is free so to move by a spring 39 against a movable stop, not shown, the position of which is determined by the position at any time of the feeler roll 9. Fast to the rock shaft 23 is an arm 136,

In front of the rolls 8 and 9 is a pivoted gate 129, fast to a small rock shaft 300, the gate being normally held raised, as shown, by a link 325 the top of which engages the under side of a crank 128, said crank being also fast to the rock shaft 300. The arm 136 has fast to its upper end a pin 137 which, when the arm is rocked to the left by the downward movement of the roll 9 due to the entrance of a blank between the rolls 8 and 9, moves the link 325 from beneath the crank 128 and permits the gate to fall until it rides upon the upper surface of the blank. The arm 21 has at its left-hand end a rack 43 and is connected by a spring 249 with a saddle piece 46 which is fast to a rock shaft 45. Between the arms of the saddle piece 46 there is loose on the shaft 45 a sector 44 which meshes with the rack 43, the construction being such that the right-hand under side of the sector 44 may contact with the saddle piece to rock the shaft 45 in a clockwise direction. Downward swinging movement of the lever 21 thus causes rocking of the shaft 45 in a clockwise direction through the sector 44 and the saddle piece 46, while upward swinging movement of the lever causes rocking of the shaft 45 in a counter-clockwise direction through the spring 249. Fast to the rock shaft 45 at the end remote from the observer is a segmental gear 48, which meshes with a longitudinally slidable rack bar 49 so that any rocking movement of the shaft 45 moves the rack bar 49 in one direction or the other. This rack bar, in the patented machine, is connected unyieldingly through gearing to a plate 55 having on it stops in the form of wedges 67, the positions of which determine the extent to which the gage roll 70 of the splitting mechanism may rise above the edge of the knife. This splitting mechanism, except for the automatic control which has been outlined above, is similar to that of an ordinary splitting machine and comprises a gage roll 70, a knife 75 and a feed roll 74 held up by heavy springs. The wedges 68 on the bearings of the gage roll 70 and the co-operating wedges 67 on the sliding plate 55 are shown in Fig. 3.

Also fast to the rock shaft 45 is a ratchet wheel 135 on one-half of the periphery of which are formed ratchet teeth 139 pointing in one direction and on the other half ratchet teeth 134 pointing in the other direction. A pawl 131, pivoted to the frame of the machine and arranged at the proper time to contact with the teeth 139, is normally held out of engagement with these teeth by being pivoted to the lower end of a link 130, the upper end of which is pivoted to the gate 129. Consequently, as long as the gate is held up either as shown by the arm 325 or by riding upon the upper surface of a blank which has been presented to the machine, the pawl 131 is inoperative. It becomes operative as soon as

the blank passes from beneath the gate and permits the gate to fall; and it becomes inoperative again only after the gate has been raised. A pawl 140 is urged toward the teeth 134 at all times by a spring 142, but is normally held out of contact with these teeth by a rod 143 the lower end of which presses down the tail of the pawl. This rod 143 is pivoted to the left-hand end of an arm the right-hand end of which is fast to the near end of a rock shaft 145. The remote end of this shaft has fast to it a rod 146 upon which a shoe 148 is adjustably fastened by a set screw 147.

In both the present machine and the patented machine the finally adjusted position of the rack bar 49 controls the setting of the wedges 67 of the splitting or grading mechanism and determines the thickness to which the blank will be split; and before proceeding to describe the differences in the machines the operation of the mechanism by which the bar is adjusted will be briefly described. The machine is normally at rest in the position shown, with the gate 129 raised and the rolls 8 and 9 close together. As the forward end of a blank is fed between the rolls, the feeler roll 9 is depressed thereby allowing the segmental rack 43 to be pulled down by the spring 39. This causes the sector 44 to engage the saddle piece 46 and thereby to rotate the shaft 45 and with it the ratchet wheel 135 in a clockwise direction, thus moving the rack bar 49 to the right. Meanwhile the rocking of the shaft 45 has released the gate 129 so that it rides upon the upper surface of the blank but will be free to fall and thereby move the pawl 131 to operative position as soon as the rear end of the blank passes from beneath it. The blank is now moved forward by the rolls 8 and 9. Until the forward end of the blank raises the shoe 148, the shaft 45 is free to turn in either direction, and consequently the rack bar moves back and forth in accordance with the thickness of the blank at the locality engaged by the rolls 8 and 9. As soon, however, as the forward end of the blank raises the shoe 148, the pawl 140 is thrown into engagement with the teeth 134 so as to prevent the ratchet wheel 135 from turning in a clockwise direction. This prevents any further movement of the bar 49 to the right, this being the direction in which it has been moved by the thicker localities of the blank encountered by the rolls 8 and 9. The shaft 45 is, however, still free to turn in a counter-clockwise direction to move the bar 49 to the left, this being the direction in which it is moved when successively thinner localities are encountered by the rolls 8 and 9. The part of the blank which now passes between the rolls 8 and 9 is felt of or gaged. If thicker spots are encountered, they impart no movement to the bar 49, but any spot encountered which is thinner than the thinnest

preceding spot, moves the bar 49 to the left, this response to successively thinner spots continuing until the rear end of the blank passes from beneath the gate 129 which thereupon falls and throws in the pawl 131 to lock the shaft 45 from turning in a counter-clockwise direction. At this stage the pawls 131 and 140 hold the bar 49 immovable for a time in its finally adjusted position. The operation of the parts, as thus far described, is the same as in the patented machine and reference is made to the patent for a detailed description of the means for continuously rotating the rolls, the means for connecting the arm 21 with the carrier of the roll 9 and all other means which are not specifically described in the present specification.

In the patented machine the bar 49 is connected by gearing to the wedges 67 so that, whenever the bar is adjusted, the wedges are adjusted, the construction being such that the bar and the wedges cannot be moved independently. As a result of this construction any blank fed to the machine should pass entirely through the splitting mechanism before the next one is fed to the machine. In that machine the gate 129 remains closed until the blank has been split and passes from between the rolls 70, 74. At that time, and not until then, the gate 129 is raised to permit the next blank to be presented to the machine. In other words, after a blank has been presented to the machine, it is impossible to present a succeeding blank until the first blank has passed entirely through the splitting mechanism. This construction renders the patented machine slow in operation; and it is to the remedying of this defect that the present invention is directed.

In the present machine, the rack bar 49 is not connected directly with the wedges but is indirectly connected through two wedge-setting mechanisms which are operated alternately to set the wedges, so that, after the wedges have been set in accordance with the thickness of a given blank, which is passing through the machine, a succeeding blank may be presented to the feeler rolls 8 and 9 before the first blank has left the machine.

The wedges 67 and the sliding plate 55 of the present machine are similar to those of the patented machine except that the rack teeth are formed on the rear of the plate instead of on the front. Meshing with these teeth is a pinion 301 mounted on the upper end of a rotatable shaft 302, the lower end of which carries a second pinion 303, said latter pinion meshing with teeth on a rack bar 305 having a forked forward end on the extremities of the arms of which are mounted rolls 307, 309. Located between the rack bar 49 and the rack bar 305 are the wedge-setting mechanisms which have been referred to above and are shown best in Fig. 2. It will now be under-

stood that a blank fed to the machine first operates, as in the patented machine, to set the rack bar 49 and then the rack bar 305 is adjusted through one or the other of the wedge-setting mechanisms to adjust the wedges 67 in accordance with the position in which the rack bar 49 has been set. As soon as this has been accomplished and the forward end of the blank has raised the gage roll 70 preparatory to being split by the knife, the gate 129 is raised and another blank may be fed to the machine.

Before proceeding to the description of the plurality of setting mechanisms, the operation of the gate 129 will be described. As a blank enters between the rolls 70, 74, the roll 70 is raised, and as it passes from between these rolls the roll 70 falls. In the patented machine, the gate 129 is raised when the roll 70 falls, but in the present machine, the gate is raised when the roll is raised. A rod 311 has a strap at its upper end which encircles the journal end of the roll 70 so that the rod is moved up and down with the roll, the lower end of the rod being adjustably fastened to a member 313 which is pivoted at 315 to a lever 317. The member 313 is in effect merely an extension of the rod 311 and is provided merely to permit the effective length of the rod to be adjusted if desired. The lever 317 is pivoted at its rear end at 319 to the frame of the machine and at its front end to an arm 321 which is urged at all times to the right by a spring 323. Located behind the arm 321, as viewed in Fig. 1, is the arm 325 which is pivoted to the frame of the machine at 327 and extends above the level of the top of the arm 321. It is this arm 325 which is holding the gate 129 raised or open in the figure. This arm is urged at all times to the right by a spring 329. As has been explained above, when a blank enters between the feeler rolls 8 and 9, the arm 136 is swung to the left. During the swinging the pin 137 causes both of the arms 321 and 325 to swing to the left with the arm 136. The parts remain in this position while the blank is passing beneath the gate, it being understood that the gate is at this time held from falling merely by the fact that it is riding upon the blank. As soon as the blank passes from beneath the gate, the gate falls. At this time the under surface of the arm 128 is below the level of the upper end of the arm 325 but is above the level of the upper end of the arm 321. Both arms have been swung from beneath the crank arm and are held in that position by the pin 137 against the force of the springs 323, 329. The parts remain in this position until the rear end of the blank passes from beneath the rolls 8 and 9 whereupon the heavy springs (shown in the patented machine), which support the roll 9, raise that roll and also the lever 21. This

swings the arm 136 back to the position shown and permits the spring 323 to swing the arm 325 to the right. The arm 325 is held in this position by the pin 137 against the force of the spring 329. The parts remain in this position until the rear end of the blank passes from beneath the rolls 8 and 9 whereupon the heavy springs (shown in the patented machine), which support the roll 9, raise that roll and also the lever 21. This

321 underneath the crank 128. The parts remain in this position until the forward end of the blank raises the roll 70. This raises the lever 317 about its pivot 319 and through 5 the arm 321 raises the arm 128 and with it the gate 129 and permits the spring 329 to pull the arm 325 beneath the crank 128. When, thereafter, the blank passes from between the rolls 70, 74 and the roll 70 falls, the parts 10 assume the position shown with the gate held raised by the arm 325. It should be noted that the gate is raised as soon as the roll 70 is raised and that the purpose of the arm 325 is principally to ensure that the gate is held 15 open. In practice a second blank will be fed beneath the gate as soon as the first blank raises the roll 70 preparatory to being operated upon by the grading mechanism.

Referring now more particularly to Fig. 2, 20 the plurality of setting mechanisms, which controls the position of the wedges 67 in accordance with the position to which the rack bar 49 has been adjusted by a blank, will now be described. A rotary shaft 331, mounted in 25 the frame of the machine, has mounted loosely on its end a gear 333 which may be driven continuously from any suitable rotating member of the machine. This gear is connected with the shaft by a one-half revolution clutch indicated as a whole at 335. This clutch will not be described, since its construction per se forms no part of the present invention, other than to say that it is controlled by a dog 337 in such manner that raising the dog and permitting 30 it to fall causes the shaft 331 to make half a revolution. The dog is vertically slidable in a suitable guideway in the frame of the machine and has near its upper end a notch 339 with which a pawl 341 co-operates. This 35 pawl is pivoted on a slide 343 and is urged toward the dog 337 at all times by a spring 345. A pin 347 carried by the frame of the machine is arranged in the upward path of the tail of the pawl. Assuming that the parts 40 occupy the position shown in Fig. 1, which is the normal position, and that the slide 343 is raised, the pawl 341 will lift the dog 337 and thereby release the one-half revolution clutch. 45 As soon, however, as the clutch is released, the pin 347 will trip the pawl and allow the dog 337 to fall so as to limit the movement of the shaft 331 to one-half a revolution. The slide 343 is raised by the passage of a blank 400 beneath a roller 349 which is rotatably 50 mounted in bearing bosses 351 carried by a yoke 353, the bearing bosses being vertically slidable in guideways 355 formed in stationary parts of the machine. A lifting lever 357 has one end connected with the slide 343 by a pin 55 and slot connection and the other end fulcrumed about a fixed pivot pin 359, while a second pivot pin 361 connects the lever with the yoke 353. Consequently, as the blank is moved forward by the chain 154, as in the patented machine, and carried beneath the roller 60 65

349, the roller 349 and lever 357 are raised, and the pawl 341 raises the dog and then lets it fall so as to control the clutch in the manner which has been described to impart a half revolution to the shaft 331. Fig. 1 shows the normal 70 positions of the parts. Fig. 2 shows the parts in the positions they occupy just after the half revolution has been completed. As soon as the blank has passed from beneath the roller 349, the pawl 341 will re-engage the notch, 75 as shown in Fig. 1, so as to be in position to raise and release the dog when the next blank passes the roller 349.

Loose on the shaft 331 are two setting cams 363 and 563 which co-operate respectively with the rolls 307, 309 on the fork of the rack bar 305. These cams and their associated parts have been shown in separated relation in order to promote clearness of illustration but, as will presently appear, some of these parts are integral with one another. Referring first to the cam 363, which has just been rotated through 180 degrees to push the rack bar 305 to the left and thereby to set the wedges 67 in accordance with the thinnest spot in a selected area of the blank 400, this cam has fast to the remote side a collar 367 provided with a notch 369 which, when the blank 400 was presented to the feeler rolls 8 and 9, was in engagement with a pawl 371. This pawl is pivoted on a toothed sector 373 which is loose on the shaft 331 and meshes with the rack 49, a spring 375 being provided to hold the pawl in engagement with the notch 369. Fast to the near side of the cam 363 is a second collar 377 having teeth 379 which co-operate with a detent 381 carried by a socketed member 383, which is pinned to the shaft 331 at 385. A coiled spring 387, fast at one end to the socketed member and at the other end to the collar 377 tends to turn the collar, and with it the setting cam 363 in a clockwise direction so as to hold the notch 369 in engagement with the pawl 371 while the rack bar 49 is being moved to the left in response to successively thinner spots in the blank. A trip member 389, fast to a stationary part of the machine, is located in the path of rotation of the detent 381 and is adapted to engage the tail of the detent and thereby disengage it from the teeth 379 when the shaft 331 shall have been given another half revolution.

When the blank 400 was presented to the feeler rolls 8 and 9, the cam 363 was in the angular position which the cam 563 is shown as occupying; and the detent 381 was held out of engagement with the teeth 379. The entrance of the forward end of the blank between the rolls, depressed the roll 9 and thereby moved the rack bar 49 to the right. This swung the sector 373 in a counter-clockwise direction, the pawl 371 engaging the notch 369 and swinging the cam 363 in the same direction. This movement of the cam 100 105 110 115 120 125 130

wound up the spring 387. As the blank moved forward, the rack bar 49 moved to the right or the left according to the thickness of the blank at the points engaged by the rolls 8 and 9, and the cam 363 swung correspondingly until the forward end of the blank lifted the shoe 148 and released the pawl 140, after which no further movement to the right of the rack bar 49 was permitted. 5 That is, there was no longer any response by the rack bar 49 to successively thicker spots encountered by the rolls 8 and 9. As successively thinner spots were encountered, the rack bar moved to the left. Such movements 10 moved the sector 373 in a clockwise direction; and the coiled spring 387 caused the cam 363 to move with the sector. Such movements of the rack bar 49 in response to successively thinner spots in the blank continued until 15 the rear end of the blank passed from beneath the gate and the pawl 131 was thrown in. At this time the angular position of the cam 363 corresponded to the position of the rack bar 49 and consequently to the thickness of 20 the thinnest spot encountered by the rolls 8 and 9 in a selected locality of the blank. It should be noted, that the thicker is this thinnest spot, the farther the setting cam will have been eventually turned in a counter 25 clockwise direction from its normal position, and the thinner the spot the less it will have been turned. As the blank 400 passed beneath and lifted the roll 349, the shaft 331 was turned half a revolution in the direction 30 indicated by the arrow. At the moment when the half revolution of the shaft 331 was started, the tail of the detent 381 moved past the member 389 and its operative end engaged the teeth 379 so that the cam 363 was turned into the position shown, the turning of the 35 cam serving by engagement with the roll 307 to push the rack bar 305 to the left and to rotate the pinion 303, the shaft 302, and the pinion 301 thereby moving the plate 55 with its wedges 67 a distance transversely of the machine dependent upon the position in 40 which the cam 363 was set and therefore upon the thickness of the thinnest spot in the stock which was encountered by the rolls 8 and 9 during the feeling operation. 45

In the patented machine the wedges 67 are held normally away from the wedges 68 on the bearings of the roll 70 by a spring 71, but in the present machine, as shown in Fig. 3, the spring 71 is reversed in its connections so as to hold the wedges 67 and 68 normally in contact, the pinion 301 being located at the rear of the plate 55 instead of in front of it as in the patented machine. 55

The setting cam 563 and its associated parts are similar to the cam 363 and its associated parts; and no detailed description of the cam 563 will be given. This cam and its associated parts have, however, been given numer- 60

als like those of the cam 363 but increased by 200.

The operation of the machine from the time the blank 400 was presented to the rolls 8 and 9 until it reaches the position shown 70 in Fig. 2 has been described. As this blank continues its forward movement the forward edge presently enters between the rolls 70, 74 and raises the roll 70. As soon as this occurs, the gate 129 is raised, as has been explained, and a second blank may be presented to the machine just before the splitting of the blank 400 begins. The raising of the gate 129 removes the pawl 131 from 75 engagement with the ratchet 135 and permits the rack bar 49 to be moved to the left into position shown in Fig. 1. This causes the sector 373 to be swung back into the position shown in Fig. 1 with the pawl 571 in engagement with the notch 569 of the collar 567 which is fast to the setting cam 563. Accordingly the second blank, as it passes through the feeler rolls 8 and 9, adjusts the controller 49 and moves the cam 563 in the same manner that the blank 400 adjusted the controller and moved the cam 363. When this second blank raises the roll 349, a half revolution is imparted to the shaft 331 again. This half revolution not only moves the cam 563 to set the wedges anew for the second blank, 85 but returns the cam 363 to normal position ready to be moved by the third blank when it shall have been presented to the machine. Referring now to the cam 363, the half revolution of the shaft 331 just referred to, just 90 at its completion, causes the tail of the detent 381 to strike the member 389. This releases the detent, whereupon the spring 387 turns the cam 363 until the projection 391 engages the notch 393 of the socketed member 383 so that the parts stop at such times with the cam 363 always in the same position. 95

In the operation of the machine, then, each succeeding blank may be fed to the feeler 100 rolls as soon as the preceding blank has lifted the gage roll 70 prior to being split by the knife 75 and may actuate the adjusting or setting mechanism while the adjustment of the splitting mechanism for the preceding blank is being maintained. 105

The patented machine is fitted with a marking mechanism in addition to its splitting mechanism, but this marking mechanism has been omitted from the present machine because it is merely another form of grading mechanism and its inclusion would complicate the drawings. The term grading mechanism as used throughout the claims, is intended to refer to any mechanism which acts upon or with reference to a blank so as to perpetuate or to facilitate the perpetuation of the determined degree of a selected characteristic of the blank and is not limited to the particular grading mechanism which has been illustrated. It should also be un- 110 115 120 125 130

derstood that, although two setting mechanisms have been shown in the illustrative machine, the invention is not limited to any particular number.

5 The term "main grading means" which appears below refers to a grading means, such for example as a splitting mechanism which changes the thickness or some characteristic of the blanks by operating upon 10 the blanks, as distinguished from a grading mechanism which merely sorts the blanks without operating upon them to change them in any way.

Having thus described my invention, what 15 I claim as new and desire to secure by Letters Patent is:

1. A machine of the class described having, in combination, splitting mechanism, mechanism for adjusting the splitting mechanism in accordance with the smallest extent of a selected dimension of a blank throughout a selected locality of the blank, and means whereby a succeeding blank may be caused to operate the adjusting mechanism during the time that the preceding blank is engaged by the splitting mechanism.

2. A machine for treating a series of blanks some of which are heterogeneous as to the degree of a selected characteristic possessed by them, having in combination, mechanism for grading the blanks adapted to be set in different positions so as to grade differently those blanks having different degrees of the selected characteristic, a plurality of adjustable mechanisms for setting the grading mechanism in accordance with the degree of the characteristic possessed by each blank, and means whereby a succeeding blank may be fed to the machine to adjust one setting mechanism while the grading mechanism is in the position in which it was set by another setting mechanism.

3. A machine for treating a series of blanks some of which are heterogeneous as to the degree of a selected characteristic possessed by them, having in combination, mechanism for grading the blanks adapted to be set in different positions so as to grade differently those blanks having different degrees of the selected characteristic, means for feeding the blanks thereto to be graded, a plurality of setting mechanisms adjustable by the blanks as they are fed along, and means whereby one of the setting mechanisms may be held in the position to which it was adjusted by one blank while another is being adjusted by another blank.

4. A machine for treating a series of blanks some of which are heterogeneous as to the degree of selected characteristic possessed by them, having in combination, mechanism for grading the blanks adapted to be set in different positions so as to grade differently those blanks having different degrees of the select-

ed characteristic, means for feeding the blanks thereto to be graded, a plurality of setting mechanisms adjustable by the blanks as they are fed along, and means whereby one of the setting mechanisms may be held in the position to which it was adjusted by one blank while another is being adjusted by a succeeding blank.

5. A machine of the class described having in combination grading mechanism adapted to be set and held set in different positions to treat one after another a series of blanks possessing a given characteristic in different degrees, a plurality of mechanisms for setting the grading mechanism, and means for causing the setting mechanisms to operate seriatim irrespective of the degrees of the given characteristic possessed severally by the blanks.

6. A machine for treating a series of blanks which are heterogeneous as to the degree of a selected characteristic possessed by them, having in combination, grading mechanism adapted to be set in different positions so as to operate differently upon blanks which vary in degree of a selected characteristic, a plurality of mechanisms for setting the grading mechanism, and means for causing one or another of the setting mechanisms to operate once for each blank fed to the machine.

7. A machine of the class described having in combination grading mechanism capable of being set and held set in different positions to treat blanks possessing a given characteristic in different degrees, the position in each case corresponding to the degree, a plurality of adjustable mechanisms for setting the grading mechanism, and means whereby a succeeding blank may be fed to the machine to adjust one of the adjustable mechanisms while the grading mechanism remains in the position to which it was set by another adjustable mechanism.

8. A machine of the class described, having in combination, mechanism for grading blanks adapted to be set in various positions so as to grade differently blanks which have different degrees of a selected characteristic, a plurality of mechanisms for setting the grading mechanism, and means for rendering the setting mechanisms operative one at a time.

9. A machine of the class described, having in combination, mechanism for grading blanks, a plurality of mechanisms for setting the grading mechanism in such manner as to cause it to operate differently upon different blanks, mechanism responsive to the degrees of a selected characteristic of the blanks to be graded for adjusting the setting mechanisms, and means for causing the setting mechanisms to operate successively to set the grading mechanism.

10. A machine of the class described having in combination grading mechanism adapted

to treat one after another an entire series of blanks possessing a given characteristic in different degrees each in a manner determined by the degree of the given characteristic possessed by the blank, a plurality of mechanisms for setting the grading mechanism once for each blank, and means for rendering the setting mechanisms operative one after another.

11. A machine of the class described, having in combination, mechanism for grading blanks adapted to be set in different positions in accordance with the degree of a selected characteristic, a plurality of mechanisms for setting the grading mechanism in said positions, feeler mechanism for controlling the operation of the setting mechanisms, and means for compelling the setting mechanisms to operate successively to set the grading mechanism.

12. A machine of the class described, having in combination, feeler mechanism constructed and arranged to detect a thin spot in each of a series of blanks, mechanism for grading the blanks, and a plurality of setting mechanisms responsive to the operation of the feeler mechanism for successively setting the grading mechanism.

13. A machine of the class described, having in combination, feeler mechanism, grading mechanism, and a plurality of setting mechanisms responsive to the operation of the feeler mechanism upon different blanks for successively setting the grading mechanism in accordance with the thicknesses of the thinnest spots of the blanks as detected by the feeler mechanism.

14. A machine of the class described, having in combination, feeler mechanism constructed and arranged to detect thin spots in each of a series of blanks, grading mechanism adapted to be set in accordance with the determinations of the feeler mechanism, a plurality of setting mechanisms, and means for rendering the setting mechanisms successively responsive to the operation of the feeler mechanism.

15. A machine of the class described having in combination feeler mechanism for detecting the degree of a selected characteristic of each of a series of blanks, grading mechanism adapted to be set in accordance with the determinations of the feeler mechanism, means for operating the grading mechanism once for each blank fed through the machine, a plurality of mechanisms for setting the grading mechanism, and means for rendering the setting mechanisms responsive one at a time to the feeler mechanism.

16. A machine of the class described having in combination feeler mechanism constructed and arranged to detect the thinnest spot in a selected area of each of a series of blanks, mechanism for grading the blanks adapted to be set in different positions, and a plurality of setting mechanisms located between the

feeler mechanism and the grading mechanism.

17. A machine of the class described having in combination feeler mechanism constructed and arranged to detect the smallest extent of a selected dimension of each of a series of blanks, mechanism adapted to be set in different positions for grading the blanks, and means for setting the grading mechanism in accordance with the detections of the feeler mechanism, said means comprising a plurality of setting members and means for rendering them successively operative.

18. A machine of the class described, having in combination, feeler mechanism, grading mechanism and means for setting the grading mechanism in accordance with the operation of the feeler mechanism, said means comprising a plurality of setting members, and means for moving them successively to extents dependent upon the extent of a characteristic of the successive blanks engaged by the feeler mechanism.

19. A machine for treating a series of blanks some of which are heterogeneous as to the degree of a selected characteristic possessed by them, having in combination, mechanism for grading the blanks adapted to be set in different positions so as to grade differently those blanks having different degrees of the selected characteristic, feeler mechanism, and means for setting the grading mechanism in accordance with the detections of the feeler mechanism, said means comprising a plurality of setting members, means operated by the feeler mechanism for adjusting one member, and means for imparting movement to said adjusted member to cause it to set the grading mechanism and for moving another member into position to be adjusted by the feeler mechanism.

20. A machine of the class described, having in combination, feeler mechanism, mechanism for grading blanks adapted to be set in different positions to grade differently blanks having different degrees of a selected characteristic, a plurality of mechanisms for setting the grading mechanism, said setting mechanisms being successively adjusted by the engagement of the feeler mechanism with successive blanks, and means for operating one setting mechanism to set the grading mechanism for each blank presented to the machine.

21. A machine of the class described, having in combination, feeler mechanism, grading mechanism, a plurality of members for setting the grading mechanism, one of said members being in position to hold the grading mechanism set while another is in position to be adjusted by the operation of the feeler mechanism upon a blank, and means for moving the first-named member into position to release the grading mechanism and to be adjusted by a succeeding blank and for

moving the second-named member into position to set the grading mechanism in accordance with a characteristic of the first blank.

5. 22. A machine of the class described, having in combination, grading mechanism, a plurality of cams, connections between each cam and the grading mechanism and means responsive to the passage of successive blanks through the machine for adjusting the cams angularly in succession.

10. 23. A machine of the class described, having in combination, grading mechanism, a plurality of angularly adjustable cams, connections between each cam and the grading mechanism and means responsive to the passage of successive blanks through the machine for adjusting the cams one at a time.

15. 24. A machine of the class described, having in combination, feeler mechanism, grading mechanism, a plurality of mechanisms for setting the grading mechanism, a controlling member for the setting mechanisms adjustable by the operation of the feeler mechanism upon a blank into various different positions according to the different degrees of a selected characteristic possessed by the different blanks, and means for causing one of the setting mechanisms and then another to set the grading mechanism in accordance with the adjusted position of the controlling member as different blanks are presented to the machine.

20. 25. A machine of the class described, having in combination, feeler mechanism, grading mechanism, a plurality of cams for setting the grading mechanism adapted to be adjusted one at a time by the operation of the feeler mechanism, and means for imparting to an adjusted cam that fractional part of a revolution which is equal to one divided by the number of cams.

25. 26. A machine of the class described, having in combination, feeler mechanism, grading mechanism, a plurality of cams for setting the grading mechanism adapted to be adjusted successively by the operation of the feeler mechanism, a shaft upon which the cams are mounted, and means for imparting to the shaft that fractional part of a revolution which is equal to one divided by the number of cams.

30. 27. A machine of the class described, having in combination, feeler mechanism, mechanism for grading blanks adapted to be set in differently adjusted positions so as to grade in various different ways blanks which vary in the extent of a selected dimension, a plurality of cams for setting the grading mechanism adapted to be adjusted successively by the operation of the feeler mechanism, and means for rotating the cams intermittently.

35. 28. A machine of the class described, having in combination, feeler mechanism, mech-

anism for grading blanks adapted to be set in differently adjusted positions so as to grade in various different ways blanks which vary in the extent of a selected dimension, a plurality of cams for setting the grading mechanism adapted to be adjusted successively by the operation of the feeler mechanism, a shaft upon which the cams are mounted in different angular positions, and means for rotating the shaft intermittently.

40. 29. A machine of the class described, having in combination, feeler mechanism, grading mechanism, a plurality of cams for setting the grading mechanism adapted to be adjusted successively by the operation of the feeler mechanism, a shaft upon which the cams are loosely mounted, yielding means for connecting the cams with the shaft, means whereby engagement of a blank by the feeler mechanism adjusts one of the cams angularly, means for thereafter connecting the cam positively with the shaft, means for imparting movement of revolution to the shaft, and means operated by the turning of the cam for setting the grading mechanisms.

45. 30. A machine of the class described, having in combination, feeler mechanism, mechanism for grading blanks adapted to be set in differently adjusted positions so as to grade in various different ways blanks which vary in the extent of a selected dimension, a plurality of cams for setting the grading mechanism adapted to be adjusted successively by the operation of the feeler mechanism, and means for rotating each cam after its adjustment through a fixed arc to set the grading mechanism in accordance with said adjustment.

50. 31. A machine of the class described, having in combination, a controlling member, means for adjusting the controlling member to a position corresponding to the thickness of the thinnest spot in a selected locality of a blank, grading mechanism, a plurality of setting mechanisms the members of which are successively adjusted by the controlling member, and means for successively operating the setting mechanisms to set the grading mechanism.

55. 32. A machine of the class described having, in combination, mechanism for operating upon a series of blanks, which are heterogeneous as to a selected characteristic, in such manner as to change that characteristic, and mechanism for adjusting the operating mechanism differently in accordance with the different degrees of the selected characteristic possessed by the blanks, said mechanisms constructed and arranged to maintain the adjustment of the operating mechanism while at the same time permitting the adjusting mechanism to respond to a characteristic of a succeeding blank.

60. 33. A machine of the class described, having in combination, mechanism for operating

upon blanks in such manner as to change the thickness of said blanks, mechanism for adjusting the operating mechanism in accordance with the thickness of a given blank at a thin spot, said adjusting mechanism including a controller adjustable by the blanks into different positions, means for locking the controller in the position to which it is adjusted, and means for freeing the controller to make it responsive to a succeeding blank after the operating mechanism has been adjusted by a preceding blank and before the operation upon the preceding blank has been completed.

34. A machine of the class described, having in combination, mechanism for operating upon blanks in such manner as to change the degree of a selected characteristic of the blanks, said mechanism being adjustable in accordance with the original degree of the characteristic of a given blank, an adjustable controller for governing the adjustment, means for locking the controller in adjusted position, and means for freeing the controller to make it responsive to a succeeding blank after the operating mechanism has been adjusted by a preceding blank and before the operation upon the preceding blank has been completed.

35. A machine of the class described, having in combination, splitting mechanism, a plurality of adjustable mechanisms for setting the splitting mechanism in accordance with the thickness of successive blanks fed to the machine, and means for causing the setting mechanisms to operate in succession.

36. A machine of the class described, having in combination, splitting mechanism, a plurality of adjustable mechanisms for setting the splitting mechanism in accordance with the thickness of the thinnest spots in selected portions of successive blanks fed to the machine, and means for causing the setting mechanisms to operate in succession.

37. A machine of the class described, having in combination, feeler mechanism, splitting mechanism, and means for setting the splitting mechanism in accordance with the thickness of blanks fed successively to the machine, said means comprising a plurality of setting members, and means for rendering them successively operative.

38. A machine of the class described, having in combination, a single splitting mechanism, a plurality of setting mechanisms, and means for causing the setting mechanisms to operate in succession to set the splitting mechanism.

39. A machine of the class described, having in combination, a single splitting mechanism, a plurality of setting mechanisms adapted to set the splitting mechanism in accordance with the thickness of successive blanks fed to the machine, and means for causing the setting mechanisms to operate in succession.

40. A machine of the class described having, in combination, feeling mechanism for detecting the thinnest spot in a selected locality of a blank, adjusting mechanism controlled by the detection of the feeling mechanism, splitting mechanism set in accordance with the position of the adjusting mechanism, and means whereby a succeeding blank may be causing the operation of the adjusting mechanism during the time that the splitting mechanism remains set in position to operate upon a preceding blank.

41. A machine of the class described having, in combination, splitting mechanism, mechanism for adjusting the splitting mechanism in accordance with the degree of a selected characteristic of a blank fed to the machine, and means whereby a succeeding blank may be caused to operate the adjusting mechanism before the splitting of the preceding blank has been completed.

42. A machine of the class described having in combination feeler mechanism, grading mechanism responsive to the determinations of the feeler mechanism said grading mechanism including a roll adapted to be engaged and moved by a blank as it passes through the machine, a gate in front of the feeler mechanism which controls the presentation of blanks to the feeler mechanism, and connections between the roll and the gate such that engagement of the roll by the blank causes the gate to be opened.

43. A machine of the class described having in combination feeler mechanism, grading mechanism responsive to the determinations of the feeler mechanism, said grading mechanism including a gage roll adapted to be lifted by a blank passing through the machine, a gate located in front of the feeler mechanism, and means for opening the gate when the gage roll is lifted.

44. A machine of the class described having in combination feeler mechanism, grading mechanism including a pair of feed rolls and a splitting knife, one of said rolls being a gage roll adapted to be raised by the passing of a blank beneath it, a plurality of inclines adjustable into different positions to limit the extent of movement of the gage roll and hence to determine the thickness to which a blank will be split, a controller, means for moving the controller into a position corresponding to the thickness of the thinnest spot in a blank as detected by the feeler mechanism, and means operating thereafter to move the inclines into a position determined by that of the controller.

45. A machine of the class described having, in combination, splitting mechanism including a knife, a pair of rolls and a stop for one of the rolls the position of which stop determines the extent to which said roll may be moved away from the other roll, an adjustable controller for the stop adapted to

be adjusted and locked in adjusted position by the passage of a blank through the machine, and means for freeing the controller and making it responsive to a succeeding blank after the stop has been adjusted through the controller by the preceding blank and before the splitting of the preceding blank has been completed.

46. In a machine of the kind described in combination, means for detecting the grade of successive blanks according to their thickness, governing means to control the admission of blanks to said detecting means, grading mechanism, including a splitting knife, to grade the detected blanks in accordance with said detecting means, and actuating means to actuate said governing means to admit to said detecting means a succeeding blank before a preceding blank has reached said splitting knife.

47. In a machine of the kind described, in combination, detecting means for measuring a blank, means of the kind herein defined as main grading means for subsequently grading the blank in accordance with said measurement, means for advancing the blank after being measured, automatic means responsive to said detecting means and operative on the advance of the blank through the machine after having been measured, for adjusting said grading means in accordance with said measurement, and a positive lock for thereafter locking the grading means in its adjusted position whether or not a blank is then being graded thereby.

In testimony whereof I have signed my name to this specification.

WILLIAM C. STEWART.
